[57] **CLAIM**

An ornamental design for a guitar tuner with an analog-simulative liquid crystal display, as shown and described.

DESCRIPTION

FIG. 1 is a perspective view of a guitar tuner with an analog-simulative liquid crystal display showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is an enlarged fragmentary view of the analog-simulative liquid crystal display in a non-operational position; and,

FIG. 9 is an enlarged fragmentary view of the analog-simulative liquid crystal display in an operational position. The broken line showing of the printed matter "QWiK TUNE" in FIG. 1 is for illustrative purposes only and forms no part of the claimed design.
